Patented Jan. 1, 1963

194,322

TOY BALL PROJECTOR

Seymour Weinstein, New York, N.Y.
(120 E. 19th St., Brooklyn, N.Y.)

Filed Apr. 7, 1961, Ser. No. 64,652

Term of patent 14 years

(Cl. D34—5)

FIGURE 1 is a front elevational view of a toy ball projector showing my new design;

FIGURE 2 is a rear elevational view thereof with the lower portion in a depressed position;

FIGURE 3 is a top plan view thereof;

FIGURE 4 is a bottom plan view of FIGURE 1; and

FIGURE 5 is a bottom plan view of FIGURE 2.

I claim:

The ornamental design for a toy ball projector, substantially as shown.
